UNITED STATES PATENT OFFICE.

HERBERT E. RIDER, OF BROOKLYN, NEW YORK, ASSIGNOR, BY MESNE ASSIGNMENTS,
TO PETER T. LEHR AND JAMES H. MURPHY, BOTH OF NEW YORK, N. Y.

SPARK-PLUG.

1,249,830.

Specification of Letters Patent. Patented Dec. 11, 1917.

Application filed June 1, 1917. Serial No. 172,324.

To all whom it may concern:

Be it known that I, HERBERT E. RIDER, a citizen of the United States, and a resident of Brooklyn, in the county of Kings and 5 State of New York, have invented a certain new and useful Spark-Plug, of which the following is a specification, the same being a full, clear, and exact description of the invention, such as will enable others skilled 10 in the art to which it appertains to make and use the same.

This invention relates to means for producing sparks by the interruption of an electric circuit, which may be employed for various purposes, and the invention pertains primarily to devices for igniting the explosive charges in internal combustion engines of the hydrocarbon type in which, by the use of relatively movable electrodes, I 20 prevent to as great an extent as possible the accumulation of the products of combustion or other foreign matter which might tend to produce a short circuit or to otherwise interfere with the operation of the plug, the 25 object of the invention being to improve, simplify and lower the cost of manufacture of the same.

To attain the desired end, the invention consists in the construction arrangement and 30 operation of parts hereinafter set forth which may be easily and accurately assembled and also removed for cleaning purposes and which are reliable and efficient in practical operation.

35 In the drawings which accompany and form a part of this specification and which illustrate one embodiment of the invention, Figure 1 represents a longitudinal section of an article constructed according to this 40 invention; and

Figs. 2 and 3 are detail views in elevation of relatively movable electrodes in which the invention is embodied.

Like letters of reference indicate like 45 parts in all the views.

Referring particularly to the drawings, 1 denotes the wall of a combustion chamber of an engine preferably of the hydrocarbon type and adapted to be mounted on a vehicle. The tubular metal shell or casing 2 of the plug is preferably externally threaded 50 at the lower open portion thereof to provide means for attachment to the said wall, and

it may be also screw threaded at the upper part of the same for engagement with a bushing 3, the intermediate body portion of the shell being preferably enlarged and formed with a plurality of annular angular faces.

The insulating member or core 5 which may be made of porcelain, mica, cement or similar di-electric material is partly inclosed within and partly extends above the shell 2 and is preferably formed with an exterior central shouldered portion to respectively abut a shoulder formed at the interior of the shell and to also face the inturned upper part of the bushing 3 which encircles the core, direct contact between the parts at the said opposed points being prevented by the use of suitable gaskets or packing 17 preferably comprising a fibrous material.

The upper portion of the insulating member preferably extends in a vertical direction through the orifice of the bushing, and the lower part of the said member depends within the open cylindrical chamber of the shell, and throughout the said di-electric element there extends an axial opening or longitudinal bore 6 to contain an electrode support, as in the present instance a screw 8 having a nut 9 in threaded engagement therewith at the top of the insulating member. A threaded thumb-nut 10 or connecting member is mounted in threaded engagement with the screw 6 and is adapted to securely connect a line wire or other suitable member of an electric circuit with the screw in an electrical relation.

The lower part of the bore 6 is ordinarily 90 enlarged to form a chamber having a narrowed or contracted mouth or outlet 7 at the extreme end of the same.

The lower open portion of the shell 2 constitutes a stationary electrode which, being 95 ordinarily of ring shape, as at 4, provides a plurality of sparking points. I preferably use in connection therewith a second and movable electrode 11, which being either exterior of, but preferably located within the 100 core may be designated as a core terminal, which electrode is constructed and arranged in operation to approach *seriatim* different points of the continuous conducting element or electrode comprising the said 105 ring, whereby my device constitutes a mul-

multiple spark plug wherein multiple sparks may be obtained from a single conductor wire.

The movable electrode may be supported 5 in any approved manner as, in one example, by means of a rigid stem 12 terminating in an enlargement 13 constructed and arranged to rest upon and work within a curved seat 14, preferably of inverted-dome shape, 10 formed in a sleeve 15 which is ordinarily in threaded engagement with the screw 8, the whole constituting a sort of ball and socket joint.

By means of this arrangement of parts 15 the electrode 11 is free to vibrate or oscillate, the said movement being caused by the motion of the vehicle, or the pulsation of the engine, or by both combined, whereby it constantly changes its sparking position. The 20 contracted mouth of the sleeve 15 or of the core 5 serves to form a guard as 7 to prevent actual contact of the movable electrode with the stationary one although the two may be in close proximity to one another, the size 25 and position of the parts being so arranged that the movable electrode shall approach the stationary one sufficiently near to maintain the proper sparking distance and thereby to enable the spark to be of the desired 30 length to be most efficient in use.

Another method of supporting the movable electrode 11 may comprise a resilient stem 16 the upper extremity of which is preferably rigidly mounted in the sleeve 11 35 which is attached in threaded engagement to the screw 8. By this construction the upper extremity of the flexible stem 16 is rigidly supported by the screw 8 while the resilience of the said stem will allow the electrode 11 to vibrate or oscillate freely, the 40 said electrode being preferably made of sufficient size to prevent pitting caused by the action of sparks between the electrodes.

It is well known that the maintenance of 45 the conductivity of the electrodes is the vital and initial source of the successful operation of the spark plug. This conductivity of the electrodes is secured first, by the thorough insulation afforded by the porcelain core and 50 packing therefor, and second, by the swinging action of the movable electrode—restricted by its guard—which continuously changes its direction of approach to, and 55 distance from, different points of the stationary electrode.

No carbon or oil is likely to collect around the terminals to interfere with the circuit as there is no socket for such matter to collect in and as the oil will drip down through 60 the orifice 18 of the ring 4, while any soot or carbon scale that may form on the edge of the insulating guard will be thrown off by the impact of the oscillatory electrode stem therewith. I thus avert any danger 65 of oil resting upon the surface of the porce-

lain core or the terminals where the spark is to be produced, and I also provide means to maintain the conductivity of the relatively movable electrodes without interfering with the free access of the gas to the spark for ignition, thus doubly guarding against short circuiting the electric current and thereby impeding or destroying the 70 spark producing properties of the plug.

This swinging action of the movable electrode and diversity of contact thereof in the spark plug also eliminates the possibility of the jump of a spark through the insulating core as sometimes occurs in the use of electrodes and porcelain or cement as hitherto 80 employed, while at the same time the prevention of the accumulation of carbon on the edge of the latter is assured.

It is a well known fact that the temperature of the heat caused by the spark at the 85 terminals of the electric conductors in the ordinary spark plug is approximately 2500° Fahrenheit and that this heat has a tendency to insulate the conducting terminals and causing a misfire in the engine, and 90 often causing a leak in the insulation of the spark plug conductors.

It is another well known fact that a spark 95 will jump between electric conducting terminals at a point where the terminals are closest together. In a spark plug where the terminals are rigid, even if a plurality of terminals are used, there will be some one point between the terminals closer than the others, and a spark will continue to jump 100 between these points until overheated, notwithstanding the ordinary theory is that the spark will seek a less heated point between the terminals.

It is one of the objects of this invention to 105 cause the spark to constantly change its direction between the conducting terminals by the constant oscillation of the movable electrode in close proximity to the ground terminal 4, thus preventing insulation by making it impossible for heat to concentrate at 110 any one point for any length of time.

I wish it to be understood that I do not 115 desire to be limited to the particular use or the exact details of construction shown and described, for obvious modifications will occur to persons skilled in the art.

What I claim as my invention is:—

1. In a device of the class described, a stationary electrode comprising a continuous 120 series of contact points, a hollow dielectric element within the electrode, a movable electrode stem supported above the bottom part of the dielectric element, and an electrode comprising a weight positioned 125 at the lower portion of the electrode stem to cause the latter to vibrate with equal ease in every direction within the dielectric element when jarred, and the weight to approach any one of the said continuous con- 130

tact points, according to the direction of movement of the spark plug.

2. In a device of the class described, a stationary electrode comprising a continuous series of contact points, a hollow dielectric element within the electrode, a movable electrode stem supported above the bottom part of the dielectric element, and an electrode comprising a weight positioned at the lower portion of the electrode stem to cause the latter to vibrate with equal ease in every direction within the dielectric element when jarred, and the weight to approach any one of the said continuous contact points, according to the direction of movement of the spark plug, and also means to prevent the abutment of the weight with any of the continuous contact points.
3. In a device of the class described, a stationary electrode comprising a continuous series of contact points, a hollow dielectric element within the electrode, a movable and flexible electrode stem supported above the bottom part of the dielectric element, and an electrode comprising a weight positioned at the lower portion of the electrode stem to cause the latter to vibrate with equal ease in every direction within the dielectric element when jarred, and the

weight to approach any one of the said continuous contact points, according to the direction of movement of the spark plug. 30

4. In a device of the class described, a stationary electrode comprising a continuous series of contact points, a hollow dielectric element within the electrode, a movable electrode stem supported above the bottom part of the dielectric element, and an electrode comprising a weight positioned at the lower portion of the electrode stem to cause the latter to vibrate with equal ease in every direction within the dielectric element when jarred, and the weight to approach any one of the said continuous contact points, according to the direction of movement of the spark plug, the dielectric element preventing the abutment of the weight with any of the continuous contact points. 35

In testimony of the foregoing specification I do hereby sign the same in the city of New York, county and State of New York, this 3rd day of May, 1917. 40

HERBERT E. RIDER.
